STOCKING

Richard Ernst Schletter, Oak Lane, Pa., assignor
to Signature Hosiery Company, North Wales,
Pa., a corporation of Pennsylvania

Application May 7, 1949, Serial No. 2,525

Term of patent 14 years

(Cl. D47—7)

To all whom it may concern:

Be it known that I, Richard Ernst Schletter, a citizen of the United States of America, residing at Oak Lane, in the county of Montgomery and State of Pennsylvania, have invented a new, original, and ornamental Design for a Stocking, of which the following is a specification, reference being had to the accompanying drawing, forming part thereof.

Figure 1 is a perspective view of a stocking embodying my ornamental design, as it appears in use on the leg of a wearer; and

Fig. 2 is a view of the foot portion of the stocking of Fig. 1, shown in flat form and on a larger scale relative to Fig. 1.

I claim:

The ornamental design for a stocking, as shown.

RICHARD ERNST SCHLETTER.
